UNITED STATES PATENT OFFICE.

STEPHEN H. FARNHAM, OF CHICAGO, ILLINOIS.

TYPE-WRITER.

No. 881,047.

Specification of Letters Patent.

Patented Sept. 18, 1906.

Application filed May 17, 1902. Serial No. 107,782.

To all whom it may concern:

Be it known that I, STEPHEN H. FARNHAM, a citizen of the United States, residing at Chicago, in the county of Cook and State of Illinois, have invented a certain new and useful Improvement in Type-Writers, of which the following is a specification.

This invention relates to a construction of type-writer more especially adapted and intended for the use of merchants and dealers generally in making a bill and charge record and an abstract of a skeleton ledger under various headings, but can be used for any class of type-writing work where various items will make up a total and such total is to be carried to a classified list or abstract in condensed form under various headings so that a total of the different headings may be produced consecutively with the bill, statement, report, or other record without the necessity of removing the blank for the abstract or the skeleton ledger from the machine with the removal of a bill, statement, report, or other charge-record.

The objects of the invention are to construct a divided or sectional cylinder or roller-platen, one division or section of which is utilized for the making thereon of the bill, statement, report, or other record, and the other division or section of which is utilized for making the skeleton ledger; to enable either division or section of the divided cylinder or roller-platen to be actuated independently or to lock both divisions or sections together to be actuated simultaneously; to furnish independent actuating means for advancing each division or section of the cylinder or platen, one of which means when the divisions or sections are locked together serving as the means for advancing both divisions or sections simultaneously; to apply an escapement for the division or section of the cylinder or platen carrying the blank for the abstract of skeleton ledger for enabling a line-by-line advance of a division or section to be attained, as required; to construct the divisions or sections of the cylinder or platen with interlocking means which can be brought into engagement for advancing the cylinder or platen as a whole; to control the division or section of the cylinder or platen which carries the blank for the abstract of skeleton ledger by a spring through which the advance of the division or section is made; to provide an escapement for the controlling

spring to regulate the advance of the division or section of the cylinder or platen actuated by the spring a line or line-space with each release of the escapement, and to improve generally the construction and operation of the cylinder or platen and the actuating means connected therewith for enabling the work to be accomplished.

The invention consists in the features of construction and combinations of parts hereinafter described, and pointed out in the claims.

In the drawings, Figure 1 is a sectional plan view of the cylinder or platen and its actuating devices in one form of construction and arrangement; Fig. 2, a similar view to Fig. 1, showing a construction and arrangement employing a controlling-spring and an escapement for one division or section of the cylinder or platen; Fig. 3, an end elevation showing the dog or pawl and the stop for advancing the cylinder or platen in the construction and arrangement of Fig. 1; Fig. 4, an end elevation, partly in section, showing the preferred form of escapement for the construction and arrangement of cylinder or platen of Fig. 2; Fig. 5, a front elevation of the escapement of Fig. 4 on an enlarged scale; Fig. 6, a detail showing a modified construction and arrangement of escapement; Fig. 7, a cross-section of the cylinder or platen of Fig. 2, showing the controlling-spring for one division or section of the cylinder or platen; and Fig. 8, a detail in sectional plan, showing a modified construction and arrangement for mounting one division or section of the cylinder or platen on the other division or section.

The cylinder or roller-platen can be of any diameter and length desired to suit the construction of type-writing machine and the work to be done. The cylinder or roller-platen, as shown, is constructed in two divisions or sections, one of which is of greater length than the other. The longer division or section A is made of an outer shell or covering *a*, of vulcanized rubber or other suitable material, and an inner tube or hollow center *a'*, made of wood or other suitable material. The division or section B of the cylinder or platen is made of an outer shell or covering *b*, of vulcanized rubber or other suitable material, and an inner tube or hollow center *b'*, of wood or other suitable material. The diameter of the two divisions or sections of the cylinder is

the same, so that when sections abut the diameter of the cylinder or platen as a whole will be equal its entire length. The outer end of the division or section A has attached thereto a plate A' with a hub or bearing A², and, as shown, the plate is secured in position by screws a² entered into the wood portion or center of the cylinder division or section, and the hub or bearing is attached to the rod or shaft on which the cylinder or platen as a whole is mounted by a set-screw a³, the end of which engages the shaft or rod. The inner or abutting end of the division or section A of the cylinder or platen has secured thereto a plate C, having a hub or enlarged center c, extending out from which and surrounding the shaft or rod on which the cylinder or platen is mounted is a sleeve C', having adjacent to its outer end a hub or enlarged center c' in the construction shown in Fig. 1. The plate C is attached to the end of the division or section A of the cylinder or platen by screws c², entered into the wood or hollow center of the division or section. The inner or abutting end of the division or section B of the cylinder or platen has secured thereto a plate D, having, as shown in Fig. 1, a central opening with a contact edge d to travel on the hub or enlarged center c of the plate C and furnish a support for the end of the division or section B and bring the periphery of the two divisions or sections in the same plane. The outer face of the plate D has a circumferential rim d' to contact the face of the plate C and reduce the friction between the two plates, the body of the plate D being cut away so as to leave a space between the two plates. The plate D is of a diameter to fit within the outer shell or covering of the division or section B, and the plate is attached in position by screws d² entered into the wood or hollow center b' of the division or section.

A plate or disk E, having peripheral ratchet-teeth e, is attached to the hub or enlarged center c' of the sleeve C'. The plate or disk E has a rim or hollow hub e', through which passes a locking-screw e², the end of which is entered into the hub or enlarged center of the sleeve, so that with the turning of the shaft or rod on which the sleeve is mounted the plate will be revolved or turned. A plate or disk F, having a series of peripheral ratchet-teeth, is attached to the outer end of the division or section B of the cylinder or platen. This plate or disk F on its outer face has an annular rim or flange f', through which passes a set-screw f², by means of which the plate or disk F and the division or section B of the cylinder or platen can be locked to the plate or disk E for the divisions or sections of the cylinder or platen to be simultaneously advanced, it being understood that when the two plates or disks are not interlocked each division or section of the cylinder or platen can be advanced or turned independently.

The plate or disk F is secured to the end of the division or section B of the cylinder or platen by screws f², entered into the wood or hollow center of the division or section. The plate or disk E is locked to the sleeve C' of the plate C, which is secured to the end of the division or section A of the roller or platen, and the division or section A is locked to the rod or shaft on which the cylinder or platen as a whole is mounted, so that with the turning of the shaft or rod the division or section A, the sleeve C', and the plate or disk E will be correspondingly turned; but such turning of the plate or disk E will not turn the plate or disk F and the division or section B of the cylinder or platen unless the two plates or disks are interlocked.

A stop G locks both of the plates or disks E and F against turning except as required, and also holds the cylinder or roller-platen in line position after each adjustment. This stop is fixedly attached at its outer end to the frame or carriage supporting the cylinder or roller-platen, in the arrangement shown, and the body of the stop is longitudinally slotted to have a side arm g and a side arm g', both of which have an elasticity or yield. These arms are arranged for the arm g to be in line with the plate or disk E, and the arm g' to be in line with the plate or disk F, and each arm at its forward or acting end has pivoted thereto a roller g², which contacts and engages the teeth of the plate or disk, as shown in Fig. 3. The plate or disk E is given a line-by-line advance by a reciprocating dog or pawl H, the acting end h of which engages successively with the teeth e of the ratchet plate or disk, and the plate or disk F is given a line-by-line advance by a dog or pawl I, the acting end i of which engages successively with the teeth f of the ratchet plate or disk, each dog or pawl being actuated in any usual and well-known manner for operating the dog or pawl of a type-writer to advance the cylinder or roller-platen. The shaft or rod J, which carries the cylinder or roller-platen in the arrangement shown in Fig. 1, passes through the sleeve C' and extends at each end beyond the end of the cylinder or platen as a whole and beyond the end of the carriage or frame carrying the cylinder or platen, and, as shown, each projecting end has fixed thereto a finger-knob J', by means of which the shaft or rod can be turned. The shaft is mounted in suitable bearings j on the ends of the carriage or frame, and, as shown, is locked against end-wise thrust or movement by collars j' and set-screws j², interposed between the knobs and the ends of the carriage or frame. The carriage or frame K, which supports the cylinder or platen and its shaft or rod in the form shown, consists of a front bar k and end bars k', the end bars having thereon the bearings j for the shaft or rod. Each end bar k' terminates in a cross-head or piece k² having ears

k^3 , between which is a collar l on a pivoting-rod L , which allows the frame or carriage to be raised and lowered, as usual.

The operation is as follows: The blank for the bill, statement, report, or charge record is inserted in the machine on the division or section A of the cylinder or platen, and the blank for the abstract, skeleton ledger, or other total memoranda or record wanted is inserted in the machine on the division or section B of the cylinder or platen. The bill, statement, report, or other record to be made is written on the blank therefor on the division or section A of the cylinder, which division or section is turned to be advanced line by line, in the usual way of operating type-writers, by the ratchet plate or disk E and its actuating-pawl H, and during the advance of the division or section A, with the ratchet plates or disks E and F disconnected, the division or section B of the cylinder or platen remains stationary, or in a fixed position, being held in such position by the arm g' and its roller g^2 of the retainer or stop. After the entries have been made on the blank on the division or section A the total of such entries is to be transferred to the blank on the section or division B under the proper heading, which total is printed on the blank, as usual in the use of type-writers. The completed bill, statement, report, or other record is removed from and a new blank for another record is inserted on the division or section A in the usual manner, and the division or section A is turned and advanced in the usual way to make the entries on the blank, and during such advance the division or section B remains stationary, or in a fixed position. After the second blank on the division or section A is completed the total thereof is transferred to the blank on the division or section B under the proper heading, the cylinder or platen being moved endwise in the usual way of moving a type-writer cylinder or platen. A third, fourth, fifth, and any number of blanks for bills, statements, reports, or records are successively entered in the machine on the division or section A and properly filled and the total of each transferred to the blank on the division or section B after each filling of a blank on the division or section A, and when the entire number of bills, statements, reports, or other records have been printed on the division or section A and the totals of the various records have been transferred to the blank on the division or section B that blank will be completed either in the form of an abstract or skeleton ledger or such other form of blank as may be used. As, for example, a merchant may desire to ascertain the total amount of groceries, fish, and meat sold daily, weekly, or monthly. If a monthly statement is wanted, added to from day to day, the operator will after making the entry from the grocery sale-ticket—for instance, on

the invoice and charge—and putting the total of the groceries in the total-amount column carry the total to the blank of the abstract, statement, or skeleton ledger to be kept and enter the same under the groceries-
70 column of such abstract, statement, or skeleton ledger. The meats purchased are entered from the meat sale-ticket onto the invoice and charge entry and the total footed, and this total is carried to the abstract, statement, or skeleton ledger and entered in the meat-column. The fish purchased are entered from the fish sale-ticket on the invoice and charge entry and the total footed and this total carried to the abstract, statement, or skeleton ledger and placed in the fish-column, it being understood that the carriage is advanced or moved endwise in each case, as usual in operating a type-writer, and that the division or section A is turned, as usual, for 85 the line-spaces through the plate or disk E and its actuating dog or pawl and that the division or section B is turned, as usual, for line-spacing by the disk F and its actuating dog or pawl I in the construction and arrangement of Fig. 1. There may be three or four entries for groceries to make one total, two or three entries for meat to make the total, and two or three entries of fish to make the total, each entry of the various purchases occupying separate line-spaces on the invoice and charge entry, and where these purchases have necessitated the advancement of the invoice or bill and charge blank or form in the regular way the division or section A of the cylinder or platen will have been turned and advanced from eight to ten line-spaces, more or less, and the division or section B of the cylinder or platen carrying the abstract, statement, or skeleton ledger 100 will have remained stationary, or in a fixed position, during the entire operation, and the three totals of groceries, fish, and meat purchased appear in the same line in their respective columns and will be advanced one 105 regular allotted line-space after the various purchases for each customer have been entered.

The bill-and-charge or monthly-statement blank when completed can be removed from the machine and another bill-and-charge or monthly statement entered into the machine on the division or section A of the cylinder or platen without disturbing the division or section B of the cylinder or platen occupied by the itemized-statement or skeleton-ledger blank, it only being advanced one regular line-space after the entry has been made on each bill-and-charge or monthly-statement blank. A complete skeleton-ledger or itemized statement will thus be had at the end of the day's work, with an entry in at least one of the three columns on their regular desired space of the blank, which entries when computed will give the total amounts of groceries, 130

meats, and fish sold for the day in the store or department, and these total amounts can be checked as a balance with the totals of the sales of the various salesmen in the store or 5 department to produce a safeguard statement, so that the proprietor may know by comparing the total of the sales with the total of the skeleton ledger or monthly statement that every sale has been billed and recorded on the monthly statement and skeleton ledger.

The construction shown in Fig. 2 also employs a divided cylinder. The divisions or sections A and B, the end plate A', the 15 ratchet plates or disks E and F, the stop or retainer G for the ratchet plates or disks, and the shaft J, its finger-knobs, and supporting frame or carriage are the same as described for the corresponding parts in Fig. 1. The 20 plate C in the construction of Fig. 2 dispenses with the hub or enlarged center c, the sleeve C', and the hub c', leaving a plate or disk with a plane face. The circumferential or annular rim d' of the plate D is deeper, 25 leaving a wider space between the faces or bodies of the two plates than in the construction of Fig. 1. The shaft J of the construction of Fig. 2 is encircled by a tubular connection M, extending the entire length of the 30 cylinder or platen and attached at one end to a center or hub m² on the plate A' and projected at its other end beyond the end of the cylinder or platen and having mounted thereon the ratchet plates or disks E and F, one of 35 which, E, is locked to a plug or hub m³, secured in the end of the tube connection, so that with the turning of the ratchet plate or disk E the division or section A of the cylinder or platen will be turned. The disks E and F are of the same construction as the 40 corresponding plates or disks in Fig. 1 and are therefore not specifically described.

The tube connection M has fixed thereto in the space between the plates C and D a collar 45 m, which is locked to the tube by a fastening screw m', the end of which passes through the tube in the arrangement shown. A constantly-wound coil-spring N is located in the space between the plates C and D, and this 50 spring is connected by a hook n to a notch or catch n' on the collar m, and its free end is attached to and bears against the inner face of a shoe N', the outer face of which runs in frictional contact with the inner face of the circumferential or annular rim d' of the plate 55 D and has sufficient frictional bearing for the force of the spring to turn the division or section B of the cylinder or platen forward when the spring is released, so as to unwind or exert forward force. The sliding friction-ring is split, so as to have a bearing on the track formed by the inner face of the rim d', and the spring is attached to the friction ring or shoe N, adjacent to one end thereof, and 60 the arrangement is one by which the spring 65

will be under a tension at all times and operate to turn the division or section B forward, or in an advance direction, and the spring after once wound to the tension required will maintain that tension for continued operation in 70 turning forward or advancing the division or section B of the cylinder or platen. The split ring by its separation exerts an outward pressure and furnishes a contact or bearing for the circumference of the ring on its track 75 by which as the limit of winding is reached the spring will be anchored or held in its constantly-wound condition, as a further winding will cause the slide-ring to slip on its track until the point is reached at which the 80 ring or shoe by its outward pressure acts as an anchor or drag against the unwinding or uncoiling of the spring, holding the spring constantly wound until released. The spring is rewound after each uncoiling or unwinding with the forward rotation of the division or section A of the cylinder or platen until the limit of the winding of the spring is reached, leaving the spring in a wound condition to advance or turn forward the division or section B with the release of the 85 spring. A reverse turning or recession of the division or section B disengages the hook n of the spring from the catch on the collar m, so that the spring is released with the reverse 90 turning, and with the cessation of the reverse turning the recoil of the spring is sufficient to carry the hook end thereof into reengagement with the notch of the collar. The ratchet plate or disk E is advanced by a reciprocating dog or pawl H, the same as in the construction of Fig. 1; but the ratchet plate or disk F is advanced by the force of the coil-spring N' and the friction-shoe. The 95 ratchet plate or disk F is held against advance and is releasable to permit an advance by an escapement of any suitable construction. The preferred form of escapement is shown in Fig. 4. This escapement O consists of a shaft or pintle o, projecting out from which at different inclinations in relation to each other are stops o' and o'', so arranged as that when one stop is turned to release the ratchet plate or disk the other stop 100 will come in position to engage a tooth of the 105 ratchet plate or disk, allowing the plate or disk to advance only a single notch, corresponding to a single line-space of the cylinder or platen. The escapement O stands vertical 110 in relation to the plate or disk, and the shaft or pintle is located in a bearing o³ and has its upper end fixedly attached to the end or head p' of an arm P, having a finger-piece p, by means of which the arm can be oscillated to 115 rock the shaft or pintle and bring the stops or catches o' and o'' into position for engaging the teeth of the ratchet plate or disk. The arm P moves over a bracket Q, having on one side a depending lug q and having on its opposite side the bearing o³, which can be 120 125 130

formed with or suitably attached to the bracket, and the bracket is attached by a suitable set-screw or otherwise (not shown) to the front rail or bar k of the frame or carriage K , carrying the cylinder or platen. The arm P is moved in a direction to release the stop or catch o' from engagement and move the stop or catch o^2 into engagement with the ratchet plate or disk F , and, as shown, the upper face of the catch o' is beveled on one side, so that with the advance of the ratchet plate or disk a tooth thereof will engage the bevel-face and automatically move the stop or catch into position for engagement and at the same time releasing the stop or catch o^2 from engagement, thus making the operation of the escapement automatic in one direction. Other forms and arrangements of escapement can be employed than that shown in Fig. 4. The escapement R (shown in Fig. 5) consists of two stops or catches r and r' , spaced at the requisite distance apart for releasing and engaging the ratchet-teeth and carried by an arm r^2 , through the finger-piece r^3 of which the stops or catches can be engaged with and disengaged from the teeth of the ratchet plate or disk.

The operation so far as entering the blanks or forms onto the divisions or sections of the cylinder or platen and making the entries on each blank or form is the same in all material respects as described for the operation of the construction of Fig. 1 except that instead of a dog or pawl for advancing the division or section B the constantly-wound spring N and the friction-shoe N' furnish the means for turning the division or section B to advance the blank or form carried thereon, such advance occurring with the release of the escapement, which allows the spring to operate.

The construction shown in Fig. 8 has the wood or hollow center portion a' extending the full length of the cylinder or platen, with the end A^2 reduced in diameter to the length of the division or section B . The outer covering b of the division or section B has an interior lining or backing b^2 with a turned rim or flange b^3 at its end, into which is threaded the attaching-screw f^3 for the ratchet plate or disk F . The end of the wood or hollow center a' has entered thereinto a metal rim or band b^4 , and at the commencement of the reduced portion A^2 of the cylinder or platen is a metal band b^5 , which bands b^4 and b^5 form a bearing or track on which the division or section B of the cylinder or platen can turn, the bands b^4 and b^5 furnishing a protection for the wood or hollow center of the cylinder or platen. The other appliances shown in connection with the construction of Fig. 1 can be used with the form of cylinder of Fig. 8.

The divided cylinder or platen, with the means for advancing or turning each division or section thereof independently and means

for turning and advancing both divisions or sections simultaneously, enables a bill, statement, report, or other record to be made on one division or section and an abstract, monthly statement; skeleton ledger, or other memoranda to be made on the other division or section without changing the operating appliances and without removing the blank or form for the abstract, statement, skeleton ledger, or other memoranda from its division or section of the cylinder or platen until the record desired is completed, and the construction also allows the cylinder or platen to be used its full length, as in the ordinary use of a type-writer, by simply interlocking the divisions or sections, so that both will be turned and advanced simultaneously.

While I have described the construction and operation of the type-writer attachment of my invention somewhat in detail and in different forms for application and use, I do not mean thereby to be confined to the forms, constructions, and arrangements otherwise than the same may be called for in the claims, as I contemplate and intend to use the invention in connection with equivalent elements and devices and the making of such mechanical changes as circumstances may render advisable or expedient without departing from the spirit of my invention, which consists in a divided or sectional cylinder or platen and means for advancing each division or section thereof independently and for interlocking the two divisions or sections for advancement simultaneously.

What I regard as new, and desire to secure by Letters Patent, is—

1. In a type-writer, the combination of a divided cylinder or platen, and means for advancing either or both sections of the cylinder or platen independently in either direction.

2. In a type-writer, the combination of a divided cylinder or platen, and means for advancing either or both sections of the cylinder or platen independently in the same direction.

3. In a type-writer, the combination of a divided cylinder or platen, and means for independently advancing each division or section of the cylinder or platen an independent step-by-step advance, substantially as described.

4. In a type-writer, the combination of a divided cylinder or platen, a separable interlock between the divisions or sections of the cylinder or platen, and means for independently and for simultaneously advancing the divisions or sections of the cylinder or platen, substantially as described.

5. In a type-writer, the combination of a divided cylinder or platen, ratchet plates or disks one for each division or section of the cylinder or platen, and means for moving each ratchet-plate or disk and giving each section

- of the cylinder or platen a step-by-step advance, substantially as described.
6. In a type-writer, the combination of a divided cylinder or platen, a separable interlock between the divisions or sections of the cylinder or platen, ratchet plates or disks one for each division or section of the cylinder or platen, and means for advancing each ratchet plate or disk, substantially as described.
10. 7. In a type-writer, the combination of a divided cylinder or platen, a ratchet plate or disk having a hub and attached to one division or section of the cylinder or platen, a ratchet plate or disk having an annular rim 15 and attached to the other division or section of the cylinder or platen, a screw for interlocking the hub and rim and connecting the two divisions or sections of the cylinder or platen as one, and means for independently 20 and for simultaneously advancing the divisions or sections of the cylinder or platen, substantially as described.
8. In a type-writer, the combination of a divided cylinder or platen, and a controlling-25 spring for one division or section of the cylinder or platen for advancing the division or section, substantially as described.
9. In a type-writer, the combination of a divided cylinder or platen, a controlling-30 spring for one division or section of the cylinder or platen for advancing the division or section, and a release-escapement for the spring-controlled division or section of the cylinder or platen, substantially as described.
35. 10. In a type-writer, the combination of a divided cylinder or platen, a controlling-spring for one division or section of the cylinder or platen, and a friction-shoe coacting with the controlling-spring and engaging the 40 division or section of the cylinder or platen, substantially as described.
11. In a type-writer, the combination of a divided cylinder or platen, a controlling-spring for one division or section of the cylinder or platen, a friction-shoe coacting with the controlling-spring and engaging the division or section of the cylinder or platen, and a release-escapement for the spring-controlled division or section of the cylinder or 45 platen, substantially as described.
12. In a type-writer, the combination of a divided cylinder or platen, a constantly-wound spring, and a friction-shoe engaged by the constantly-wound spring and engaging with one division or section of the cylinder or platen, substantially as described.
50. 13. In a type-writer, the combination of a divided cylinder or platen, a constantly-wound spring, a friction-shoe engaged by the constantly-wound spring and engaging with one division or section of the cylinder or platen, and a release-escapement for the constantly-wound spring, substantially as described.
65. 14. In a type-writer, the combination of a divided cylinder or platen, a shaft or rod having one division or section of the cylinder or platen fixedly attached thereto, a tube connection surrounding the shaft or rod, a collar fixed on the tube, a constantly-wound spring detachably connected at its inner end with the collar, and a shoe engaged by the free end of the spring and in frictional engagement with the other division or section of the cylinder or platen, substantially as described.
15. In a type-writer, the combination of a divided cylinder or platen, a ratchet plate or disk on the end of one division or section of the cylinder or platen, a constantly-wound spring, a friction-shoe engaged by the constantly-wound spring and in engagement with the division or section of the cylinder or platen having the ratchet plate or disk, and an escapement coacting with the ratchet plate or disk for releasing the spring, substantially as described.
16. In a type-writer, the combination of a divided cylinder or platen, a ratchet plate or disk on the end of one division or section of the cylinder or platen, a constantly-wound spring, a friction-shoe engaged by the constantly-wound spring and in engagement with the division or section of the cylinder or platen having the ratchet plate or disk, and an escapement consisting of a shaft or pintle, stops or catches on the shaft or pintle out of line with each other, and an arm for oscillating the shaft or pintle, substantially as described.
17. In a type-writer, the combination of a ratchet plate or disk, and an escapement consisting of a shaft or pintle having catches or stops thereon out of line with each other, one of the catches or stops having an inclined face for engagement with the teeth of the ratchet plate or disk for automatically engaging the escapement in one direction of movement, substantially as described.
18. In a type-writer, the combination of a ratchet plate or disk, an escapement consisting of a shaft or pintle having catches or stops thereon out of line with each other, one of the catches or stops having an inclined face for engagement with the teeth of the ratchet plate or disk for automatically engaging the escapement in one direction of movement, and an arm for rocking the shaft or pintle, substantially as described.
19. In a type-writer, the combination of a divided cylinder or platen, a shaft or rod having one division or section of the cylinder or platen fixedly attached thereto, a tube connection surrounding the shaft or rod, a collar fixed on the tube, a constantly-wound spring detachably connected at its inner end with the collar, and a shoe engaged by the free end of the spring and in frictional engagement with the other division or section of the cylinder or platen, substantially as described.
20. In a type-writer, the combination of a divided cylinder or platen, a shaft or rod

having one division or section of the cylinder or platen fixedly attached thereto, a tube connection surrounding the shaft or rod, a collar fixed on the tube, a constantly-wound spring detachably connected at its inner end with the collar, a shoe engaged by the free end of the spring and in frictional engage- ment with the other division or section of the cylinder or platen, and a release-escapement for the spring, substantially as described.

STEPHEN H. FARNHAM.
